CAMERA

Robert C. Zimmerman, Chicago, Ill., assignor to Bell & Howell Company, Chicago, Ill., a corporation of Illinois

Filed June 24, 1965, Ser. No. 85,897

Term of patent 14 years

(Cl. D61—1)

Fig. 1.

Fig. 2

FIG. 1 is a perspective view of a camera showing my new design; and

FIG. 2 is a perspective view of the opposite side thereof.

The bottom of the camera is substantially plain and unornamented.

The essential features of my design are shown in full lines.

I claim:

The ornamental design for a camera, as shown and described.
